UNITED STATES PATENT OFFICE.

HARRY C. MANN AND GEORGE W. LEE, OF FRANKFORD, PHILADELPHIA, PA.

DESIGN FOR A GAME-BOARD.

SPECIFICATION forming part of Design No. 12,029, dated November 9, 1880.

Application filed April 3, 1880. Term of patent 3½ years.

To all whom it may concern:

Be it known that we, HARRY C. MANN and GEORGE W. LEE, citizens of the United States, residing in Frankford, Philadelphia, in the county of Philadelphia and State of Pennsylvania, have invented and produced a new and original Design for Game-Boards, of which the following is a specification, reference being had to the accompanying drawing, forming part thereof.

Our design consists in drafting on wood, paper, or other substance the figure of a star, whose points and angles, by natural selection, shall locate positions to be used in the game for which this design is intended.

The single figure in the accompanying drawing is a perspective view of our design, showing a receptacle for the pins or pieces, and is all that is deemed necessary to fully illustrate and explain our design for game-boards.

Referring to the drawing, it will be seen that within the lines of an equilateral rectangle, A, is drawn a figure representing what is known as a five-pointed star, B, said star surrounded with two circles, C C, and the points and angles of the star are provided with small circles b, these circles locating the points or

positions to be used in playing the game for which the design is intended.

It will be seen that in drafting the figure 30 of a five-pointed star, as shown, in connecting the points of the same, and by so doing locating the angles gathered near the center, in this case they do not pass through the small circles, but connect with them, and while 35 giving the appearance to the eye of a star having an unbroken outline, and the direction of the lines kept still intact, yet the lines pass through the body of the star, connecting the small circles, which are each in their separate 40 straight lines.

Having thus described our design, what we claim as new, and desire to secure by Letters Patent, is—

A design for a game-board, consisting of the 45 figure of a five-pointed star, B, surrounded by circles C, the points and angles of the star being provided with circles b, as described, and shown in the accompanying illustration.
